(57) **CLAIM**

The ornamental design for an extension cord reel as shown and described.

DESCRIPTION

FIG. 1 is a left, front, top perspective view of an extension cord reel showing my new design;

FIG. 2 is a right, rear, bottom perspective view thereof;

FIG. 3 is a top elevational view thereof;

FIG. 4 is a bottom elevational view thereof;

FIG. 5 is a left side elevational view thereof;

FIG. 6 is a right side elevational view thereof;

FIG. 7 is a rear plan view thereof; and,

FIG. 8 is a front plan view thereof.

In the drawings, the broken lines consisting of evenly spaced dash lines depict portions of the extension cord reel that form no part of the claimed design.

1 Claim, 8 Drawing Sheets
